UNITED STATES PATENT OFFICE.

MARK W. DEWEY, OF SYRACUSE, NEW YORK, ASSIGNOR TO THE DEWEY CORPORATION, OF SAME PLACE.

ELECTRIC FIRE-ENGINE.

SPECIFICATION forming part of Letters Patent No. 446,708, dated February 17, 1891.

Application filed July 7, 1890. Serial No. 357,979. (No model.)

To all whom it may concern:

Be it known that I, MARK W. DEWEY, of Syracuse, in the county of Onondaga, in the State of New York, have invented new and 5 useful improvements in Electric Fire-Engines, (Case No. 65,) of which the following, taken in connection with the accompanying drawings, is a full, clear, and exact description.

My invention relates to certain improvements in electrically-propelled vehicles, and also in electric fire-engines.

The object of my invention is to electrically propel an electric fire-engine to and from the fire, so that it will not be necessary to employ 15 horses for this purpose, and to save the time heretofore lost in hitching them to the engine, as the electrically-propelled engine is always ready to start at the instant the alarm is sounded and does not consume any energy 20 while not in use.

The object of my invention, also, is to electrically steer an electrically-propelled vehicle or a fire-engine, so that the vehicle may be handled easily and be under the perfect control of the steersman.

To this end my invention consists in providing the electric fire-engine with a secondary battery to be carried thereon to supply current to the electric motor on the engine, 30 and in providing means whereby the electric motor on the engine for operating the pump may be disconnected from the pump and connected to the engine to propel it when desired, as it is not necessary to operate the 35 pump when the engine is being propelled to and from the fire.

My invention consists, also, in the arrangement of the motor on the engine to accommodate itself to the performance of its several 40 duties and to allow a suitable place upon the engine for the battery.

My invention consists, further, in providing means upon the vehicle for steering it electrically either by the propelling-motor or 45 a separate motor.

My invention consists, still further, in certain combinations of parts hereinafter described, and specifically set forth in the claims.

Referring to the drawings, Figure 1 is a side 5c elevation of my fire-engine with a part of the

frame, &c., broken away to show the gearing clearly. Fig. 2 is a plan view taken below the body or receptacle containing the battery and having certain parts broken away to show the apparatus beneath them. Fig. 3 is a diagrammatic view of the apparatus, circuits, and connections on the engine shown in Figs. 1 and 2. Fig. 4 is a diagrammatic view of a modified form and arrangement of the apparatus, circuits, and connections for my improved fire-engine; and Fig. 5 is a view of the compensating gear employed.

In the drawings, A represents the electric motor, suitably secured to and supported by the frame B of the engine, but preferably entirely below the back axle C, to allow a battery-receptacle D to be placed above said axle.

E is a double-acting reciprocating piston-pump fixed to the frame B about midway between the two axles of the vehicle.

F is the gearing or mechanical connection between the motor A and axle C, and F' is the gearing or mechanical connection between the said motor and the pump. In the 75 said connection to and upon the axle I preferably place a well-known compensating gear c to facilitate in turning corners, but do not limit myself to any particular form of mechanical connection either between the motor 80 and axle or between the motor and pump. The said compensating gear is shown clearly in Fig. 5 of the drawings. One wheel W is sleeved upon and turns freely on the axle C, while the other driving-wheel is keyed fast. 85 The latter is not shown in the figure. A bevel-gear r is fixed to the hub of the wheel W, and a similar gear r' is keyed to the driving-axle. Between these revolves a spur-gear s, which is driven by the motor A, and which carries 90 two small bevel-pinions t t, the latter engaging both bevel-wheels r and r', their axles being in the plane of the revolution of the large gear s. It will be obvious that resistances being equal on both wheels, if the spur-gear 95 s be turned it will carry with it both driving-wheels at the same time with equal angular velocities, the effort exerted by the motor being equal at both wheels at all times. If the

engine be turning a corner, however, the 100

greater resistance on the inside wheel retards that, while the outer wheel necessarily moves more rapidly over its longer path, and while the motor still exerts the same force on both 5 wheels the work done is distributed unequally between them through the then-revolving bevel-pinions without loss and without either wheel being necessarily slipped or disengaged.

G is a lever to operate the clutch mechanism on the motor-shaft a to disconnect the motor A from the pump and connect it with the axle C, or vice versa, when desired.

C' is the front axle of the engine. II is a fifth-wheel or circle rigidly or flexibly secured 10 to said axle and having a rack h thereon for a gear-wheel h' to work in.

i is an upright shaft extending upward from the gear-wheel h' to a large hand-wheel i' directly in front of the steersman's seat I. 15 Sleeved loosely upon the shaft i, but adapted to be fixed or keyed to the same when it is desired to steer or guide the vehicle electrically, is a gear-wheel k, adapted to be rotated by an endless screw k', fixed upon a shaft l, 20 connected to the propelling-motor or an independent or separate electric motor J beneath the seat I.

Either of the electric motors may be started, stopped, or reversed when desired, by means 30 hereinafter described.

d is the electric circuit for supplying current to the motor A, and also to the motor J when it is employed, and any other translating devices—as, for instance, the electric 35 lamp b. Said lamp b may be placed in a shunt-circuit b' with an adjustable resistance b'', and the steering-motor J is also placed in a shunt-circuit j, including an adjustable resistance j', the said shunt extending around 40 the propelling-motor.

In Figs. 1, 2, and 3 the motors are shown as being regulated or controlled in speed and direction by changing the position of the brushes upon the commutators of the motors 45 in the well-known manner not necessary to be herein repeated.

In order that the steersman may control the motors A and J, pivoted rods connect the brushes of the motors with levers A' and J', 50 conveniently located by the side of the seat I.

In the same figures the mechanical connection from the motor to the axle is on one side of the motor, and the other connection, from the motor to the pump, is on the opposite side 55 of said motor, so that it is necessary when disconnecting one mechanism from and connecting the other mechanism to the motor by means of the lever G to shift the armature slightly lengthwise or to provide a connection 60 between the clutches e e either around or through the armature, as shown. This connection consists of a shaft a, upon which the armature and the gear-wheels or pulleys c' and f are sleeved, but not capable of movement in the direction of the length of said 65 shaft.

d' is an adjustable resistance and cut-off in

the circuit of the motor A to regulate the current passing thereto.

m is a circuit-breaker on the lever J', and 70 shown in Fig. 3, to hold the circuit j open except when the handle is grasped by the operator.

In Fig. 4 both mechanical connections are on one and the same side of the motor A. 75 The pulleys c' and f are loose upon the motor-shaft, and the clutches moved by G are fixed upon a sleeve that is turned by the shaft and is capable of longitudinal movement thereon to couple either of the pulleys to the 80 shaft, as desired. In this figure the motors are shown as regulated and reversed by varying the strength of the current through them and changing its polarity through their armatures. j' and d' are the adjustable resistances in circuit with the motors to vary the 85 strength of the currents and the speed of said motors, and j'' and d'' are current-reversers in circuit with the motors to reverse the currents through their armatures to change their 90 direction of rotation when desired. These adjustable resistances and current-reversers, commonly called "current-regulating devices," are located in place of the levers A' and J', or in a suitable position to be conveniently handled by the operator in charge. 95

In Fig. 3 is also represented the flexible connections between the axle C' and the fifth-wheel II. Said flexible connections are shown 100 as four stiff springs u, two on each side of the axle, and serve to relieve the gearing from the sudden strains that it would otherwise be subjected to in moving over rough pavements.

In Fig. 4 means are shown in dotted lines for steering the engine by the propelling-motor A, and thus dispensing with the motor J. To accomplish this the shaft l is extended back to the motor A and is provided at its rear end with a miter gear-wheel, which is placed between two other mitered gear-wheels 110 fixed to a counter-shaft of the said motor, which shaft can be moved longitudinally to throw either of its gear-wheels in gear with the gear-wheel on the shaft l by means of a lever n, extending from the said counter-shaft to the front part of the vehicle and pivoted to the frame B at o. The axle C' can be crimped in either direction corresponding to the movement to the right or left of the lever n, and the speed of rotation of the shaft l 120 may be regulated by regulating the speed of the motor A.

Having described my invention, what I claim as new, and desire to secure by Letters Patent, is—

1. The combination of a vehicle having a motor mounted thereon, a battery carried upon or moving with said vehicle, an electric circuit on the vehicle for supplying current from said battery to the motor, a pump 130 carried upon the vehicle, and means to connect said motor either with the axle or wheels of the vehicle or with the pump, as desired.

2. The combination of an electrically-pro-

- 5 pelled vehicle having an electric motor mechanically connected with the axle or wheels thereof, a supply-circuit on the vehicle connected to the motor, a pump carried upon the vehicle, and means to detach said motor from the axle or wheels and to connect said motor with the pump. 7c
- 10 5. The combination, in an electrically-propelled vehicle, of an electric motor, a mechanical connection between said motor and axle, a compensating gear in said connection connected with the wheels carried by the axle to permit of their relative movement, and an electric-supply circuit on the vehicle connected to the motor. 75
- 15 6. The combination of a vehicle, an electric motor supported thereon and carried entirely beneath the back axle, and means whereby the motor can propel the vehicle or drive a pump carried thereon. 80
- 20 7. In a portable fire-engine, the combination of a wheeled vehicle, an electric-supply circuit, an electric motor on the vehicle in the circuit, a double-acting reciprocating piston-pump supported upon the frame of the vehicle, and suitable gearing connecting the motor with the pump. 85
- 25 8. The combination, with an electrically-propelled vehicle, of a supply-circuit, an electric motor on said vehicle connected with the circuit, and a steering mechanism for one of the axles mechanically connected with the said motor. 90
- 30 9. The combination of a wheeled carriage, a secondary battery supported mostly by the back axle or wheels of the carriage, an electric motor, electric connections between the battery and motor, a pump mounted on the frame of the carriage, and a suitable mechanical connection between the said motor and pump. 95
- 35 10. The combination, in an electrically-propelled vehicle, of a battery carried upon or moving with said vehicle, an electric motor, an electric circuit on the vehicle for supplying current from said battery to the motor, and a steering apparatus for the vehicle operated by the said motor. 100
- 40 11. The combination of a wheeled vehicle, an electric motor supported thereon and carried entirely beneath the back axle, a receptacle above said axle containing a battery, an electric circuit on the vehicle including the battery and motor, and suitable connections or gearing between the motor and said axle. 105
- 45 12. The combination, with a wheeled vehicle, of an electric motor supported and carried thereon, a receptacle containing a secondary battery carried upon said vehicle, one of said elements being carried above the back axle and the other entirely beneath said axle, and suitable devices whereby the motor can operate the wheels of said axle. 110
- 50 13. The combination, with a wheeled vehicle, an electric motor supported and carried thereon, and a receptacle containing a sec- 115
- 55 ondary battery carried upon said vehicle, one of said elements being carried above the back axle and the other entirely beneath said axle, and a pump carried upon said vehicle and mechanically connected with the motor. 120
- 60 14. The combination, with a vehicle, of an electric-supply circuit on the vehicle, a motor connected with the supply-circuit and mechanically connected with the vehicle to propel it, a second electric motor carried on the vehicle and connected with the supply-circuit, and means to steer the vehicle, connected with and operated by the said second motor. 125
- 65 15. The combination, with an electrically-propelled vehicle, of an electric motor, a pump upon said vehicle, means for mechanically connecting the motor with the pump, and an electric steering apparatus on the vehicle to steer the latter. 130
- 70 16. The combination, with an electrically-propelled vehicle, of a pump carried upon said vehicle and means to connect the propelling-motor with said pump to operate the same and to disconnect said motor from the vehicle, so that the latter will be at rest during the operation of the said pump. 135
- 75 17. The combination of an electrically-propelled vehicle, a pump carried upon the vehicle, an electric motor mounted upon the vehicle, and suitable means whereby said motor is connected to the pump or the driving mechanism of the vehicle to propel the same or to drive the pump. 140
- 80 18. The combination, with the axle of a vehicle pivoted in the center, of an electric motor supported upon the frame of the vehicle and flexibly connected with the said axle to cramp it in either direction to steer the vehicle. 145
- 85 19. The combination, with the axle of a vehicle pivoted in the center, of an electric motor supported upon the frame of the vehicle and connected with the said axle to cramp it in either direction to steer the vehicle. 150
- 90 20. The combination, in an electrically-propelled vehicle, of an electric motor mounted on the vehicle, an axle, wheels on said axle adapted to be turned independently of each other or with different degrees of speed, and

suitable connections between the motor and the wheels to permit of the relative movement of said wheels.

21. The combination, in an electrically-propelled vehicle, of an electric motor mounted on the vehicle, a compensating gear suitably connected to two of the wheels of the vehicle, and suitable mechanical connections or gearing between the said compensating gear and the motor to permit of the relative movement of said wheels, for the purpose described.

22. The combination of a wheeled vehicle, an electric motor supported thereon and carried entirely below the line of the axis of the wheels, means whereby the motor can propel the vehicle, and a body or receptacle above but in close proximity to the axle.

23. The combination of a wheeled vehicle, an electric motor supported thereon and carried entirely below the line of the axis of the wheels, a receptacle above said line of axis containing a battery, an electric circuit on the vehicle including the battery and motor, and a suitable connection or gearing between the motor and the said axle.

24. The combination, with a wheeled vehicle, of an electric motor supported and carried thereon, a receptacle containing a secondary battery carried upon said vehicle, one

of said elements being carried above the back axle and the other entirely beneath said axle, a pump mounted on the vehicle, and suitable devices whereby the motor can propel the vehicle or drive the pump.

25. The combination, in an electrically-propelled vehicle, of an electric motor mounted thereon, a mechanical connection between said motor and two wheels on opposite sides of the vehicle, means or devices in said connection to permit of the relative movement of the said wheels, and an electric-supply circuit on the vehicle connected to the motor.

26. In a portable fire-engine, the combination of a wheeled carriage, a receptacle supported upon the carriage, a secondary battery within the receptacle, an electric motor on the carriage, electric connections between the battery and the motor, a pump mounted on the frame of the carriage, and a suitable mechanical connection between the said motor and pump.

In testimony whereof I have hereunto signed my name this 3d day of July, 1890.
